UNITED STATES PATENT OFFICE

EUGENE C. HEILHECKER, OF BRISTOL, RHODE ISLAND, ASSIGNOR TO THE GOODYEAR'S INDIA RUBBER GLOVE MANUFACTURING COMPANY, OF NAUGATUCK, CONNECTICUT, A CORPORATION OF CONNECTICUT

DESIGN FOR A COMBINED SOLE AND HEEL

Application filed July 30, 1931. Serial No. 40,729. Term of patent 7 years.

To all whom it may concern:

Be it known that I, EUGENE C. HEILHECKER, a citizen of the United States, residing at Bristol, county of Bristol, and State of Rhode Island, have invented a new, original, and ornamental Design for a Combined Sole and Heel, of which the following is a specification, reference being had to the accompanying drawings, forming part thereof, in which

Figure 1 is a plan view of a combined sole and heel, showing my new design, and

Figure 2 is a sectional elevation taken on line 2—2 of Fig. 1.

I claim:

The ornamental design for a combined sole and heel, as shown.

Signed at Bristol, in the county of Bristol and State of Rhode Island, this 23rd day of July, 1931.

EUGENE C. HEILHECKER.
